GEORGE E. SMITH, OF SAN FRANCISCO, CALIFORNIA.

Letters Patent No. 84,914, dated December 15, 1868.

IMPROVEMENT IN AUTOMATIC STOP-COCK FOR GAS-BURNERS.

The Schedule referred to in these Letters Patent and making part of the same.

To all whom it may concern:

Be it known that I, GEORGE E. SMITH, of the city and county of San Francisco, State of California, have invented an Automatic Stop-Cock for Gas-Burners; and I do hereby declare the following description and accompanying drawings are sufficient to enable any person skilled in the art or science to which it most nearly appertains, to make and use my said invention or improvements without further invention or experiment.

My invention relates to a device for shutting the stop-cocks of gas-burners whenever the gas is accidentally extinguished, and thus preventing a waste of gas and the resulting bad odor.

This invention consists of a hoop, supported at such a height as to encircle the blaze at a little distance above the burner. The hoop is composed of an outer rim of brass and an inner rim of steel, riveted together, and is fixed at one end. The other end moves from one side to the other, operating by the unequal expansion and contraction of the two metals, and thus moves the arm of a lever which connects with a delicate holding-catch or detent. By this the stop-cock is kept open as long as the gas burns and the heat is kept up, but whenever the flame is extinguished, the contracting hoop operates the lever, and through it on the detent, freeing the arm of the stop-cock, and allowing it to close, which it does by a spring.

To more fully illustrate my invention reference is had to the accompanying drawings, forming a part of this specification, of which—

Figure 1 is a side elevation of a burner, with my device attached.

Figure 2 is a plan, showing the compound hoop.

Figure 3 is an enlarged view of the detent.

Similar letters of reference in each of the figures indicate like parts.

A is a short section of gas-pipe, which supplies the burner B, and in which is placed a stop-cock, C, which is kept closed by a spring, E.

This cock has an arm or lever, D, projecting from it, and carrying at the end a small steel catch, a.

On the pipe, or at some convenient point, is placed a plate, F, upon which the catch or detent G works, being operated by a light spring, H, so that, when the lever D is turned to open the cock, the catch a is retained by the detent, thus keeping the cock open.

An arm or standard, I, is clamped to the tube, or attached in some suitable manner, extending upward, and supporting a compound ring or hoop at such a height that it just encircles the flame, and at a little distance from it. The ring is formed of an outer band, b, of brass, and an inner one, c, of steel, the two being firmly-bolted together. One end of this ring is fastened to the standard I, and the other is free.

To the free end a lever, K, is connected, and turns on a fulcrum at L. The lower end of this lever is bent at right angles, and forms a detent, M, similar to G, and in the same plane with it.

The operation is as follows: The stop-cock C is opened, by turning the lever D until the triangular catch a passes the detent G, by which it is held. The gas is then lighted, and the flame heats the compound ring b c, which, by greater expansion of the brass, forces the free end in, and thus moves the lever K outward. This motion carries the detent M so far that G is pushed away, and the catch a is then transferred to M, by which it is held as long as the gas burns; but if by accident the gas is extinguished, the ring b c contracts and throws the free end outwards again. This withdraws the detent M by the action on the lever K, and the catch a, by its shape, passes between G and M and escapes, the spring E then closing the cock.

The present description applies to gas-burners, but my invention is applicable to steam and water-pipes, with very little alteration.

Having thus described my invention,

What I claim, and desire to secure by Letters Patent, is—

1. The compensating curb or rod, composed of two or more metals, b and c, together with the lever K, detent M, arm D, and spring E, substantially as and for the purpose described.

2. The lever K, connected with the curb, the two detents G and M, and the catch a, on the arm D, constructed and operated substantially as herein described.

In witness whereof, I have hereunto set my hand and seal.

GEO. E. SMITH. [L. s.]
